UNITED STATES PATENT OFFICE.

HERBERT S. EAMES, OF FRAMINGHAM, MASSACHUSETTS.

SKATE.

Application filed November 13, 1920. Serial No. 423,955.

To all whom it may concern:

Be it known that I, HERBERT S. EAMES, a citizen of the United States, and resident of Framingham, in the county of Middlesex and State of Massachusetts, have invented an Improvement in Skates, of which the following description, in connection with the accompanying drawings, is a specification, like characters on the drawings representing like parts.

My invention relates to skates and particularly but not exclusively to ice skates, and in this last respect relates to devices generally when provided with runners adapted to engage ice or other surfaces.

My invention will be best understood from the accompanying drawings when read in light of the following specification of a specific embodiment of my invention, while its scope will be more particularly pointed out in the appended claims.

Referring to the drawings:—

Figure 1 shows an elevation of the submitted embodiment of my invention;

Fig. 2 is a plan of the bottom of the device according to Fig. 1; while

Fig. 3 is a section on the line 3—3 of Fig. 1.

Referring to the drawings, I have shown an ice skate provided with a foot rest or plate 1 and an ice engaging member comprising the runners 2 and 3. In proportioning the parts I take advantage of the principle that a light yet rigid structure may be evolved by so disposing relatively light flexible members as to secure a great sectional moment of inertia.

To this end the plate is formed of a light somewhat flexible portion, preferably of cast aluminum and integrally formed therewith I provide the lugs or stiffening ribs 4, 5 and 6. It will be observed that it is necessary to cast the plate from one end and as the body portion is relatively thin the lugs 4, 5 and 6, particularly the ones most remote from the sprue must be small for the reason the cooling of the body portion of the plate traps metal in the cavity of the mold forming the lug. As the metal shrinks in passing from the liquid to the solid state, if the lug were large it would be impossible to form the casting without the portion adjacent the lug being misformed. For this reason, I preferably make the lugs small, positioning one at each end of the plate and one at an intermediate portion of the plate.

The runners I have shown as light, flexible members, each secured to the lugs and inside to side relation thereto by rivets 12. By this means the portions of the lugs overlapping the runners stiffen the individual runners and the pair of runners act to stiffen the plate and form a rigid assembly. Preferably for further stiffening the runners and preventing shearing of the rivets I form the lugs with shoulders 13 against which the upper edge of the runners bear.

I provide the usual heel strap 7, secured to the plate by means of pins or like fasteners 8. To stiffen the adjacent portion of the plate and provide material for receiving the pins, I provide the radially disposed ribs 9 cast integrally with the under portion of the plate. To prevent the pulling out of the pins 8 I provide the transversely disposed auxiliary pins 14 which as illustrated by Figs. 2 and 3 securely fasten the pins 8 to the plate and ribs. At the forward end of the skate I secure the toe strap 10.

Although the runners may be formed of any flexible material having wear resisting qualities, I preferably form the same of mild steel and case harden the opposite sides of the runners. By this means a hard exterior surface is provided and a relatively soft core. It will be observed that the abrasive action is greatest at the corners between the running edge 11 and the sides of the runners and that the lesser abrasion on the softer portion of running edge intermediate the sides will cause the wear to keep the runners sharp. In a skate having but one runner I may case harden both sides, but with the double runner arrangement shown I may case harden either both sides of the individual runners or but one side of each, for example the outer sides.

Although I have described one specific embodiment of my invention for illustrative purposes, it is to be understood that the same is not limited to the particular mechanical details thereof, but that wide deviations may be made therefrom without departing from the spirit of my invention.

Claims:

1. In a skate, a plurality of runners, said runners being formed of thin blades of mild steel and each having a case hardened side, a foot plate, and means rigidly securing said runners in spaced relation to said plate.

2. In a skate, a plurality of runners, said runners being formed of thin blades of mild

- steel and each having the sides thereof case hardened, a foot plate, and means rigidly securing said runners in spaced relation to said plate.
5. 3. In a skate, the combination with the plate 1 having the lugs 5 affording shoulders 13 on opposite sides of said lugs, of the runners 2 and 3, said runners being of mild steel and each having a case hardened side, and 10 means for securing the runners to said lugs with their upper edges in contact with said shoulder.
4. In a skate, a plate having a heel supporting portion of relatively thin material, 15 and said portion having a central lug with a plurality of radiating ribs formed integrally therewith.
5. In a skate, a heel strap for fastening said skate to a shoe, a pin securing said 20 heel strap to the body of the skate, and auxiliary means preventing removal of said pin.
6. In a skate, a heel strap for fastening said skate to a shoe, a pin securing said heel strap to the body of the skate, and an 25 auxiliary pin securing the first mentioned pin to the body of the skate.
7. In a skate, a foot plate of thin cast material having on its under side spaced lugs arranged longitudinally thereof and cast integrally therewith, a pair of thin flexible 30 runners rigidly secured to said lugs at opposite sides thereof; whereby said runners stiffen the plate, the plates stiffen the run-
- ners and a stiff unitary structure is provided.
8. In a skate, a foot plate of thin cast material having on its under side spaced lugs arranged longitudinally thereof and cast integrally therewith, said lugs being cut away on opposite sides thereof to form shoulders, 40 a pair of thin flexible runners at opposite sides of said lugs and bearing against said cut-away portions and said shoulders, and rivets passing through said runners and lugs for securing the parts rigidly together; 45 whereby the lugs serve as spacers for and stiffen the runners, the shoulders take the shearing stress off the rivets and the runners stiffen the plate.
9. In a skate, a foot plate having on its 50 under side spaced lugs arranged longitudinally thereof, said lugs being formed on opposite sides thereof with reduced portions providing shoulders, a pair of thin flexible runners at opposite sides of said lugs and bearing against said reduced portions and said shoulders, and rivets passing through said runners and lugs for securing the parts rigidly together; whereby the lugs serve as spacers for and stiffen the runners, the 55 shoulders take the shearing stress off the rivets and the runners stiffen the plate.
- 20 In testimony whereof, I have signed my name to this specification.

HERBERT S. EAMES.
